BOX

Benjamin S. Katz, Cincinnati, Ohio, assignor to
 The Gruen Watch Company, Cincinnati, Ohio,
 a corporation of Ohio

Application February 24, 1937, Serial No. 127,367

1 Claim. (Cl. 206—75)

My invention relates to boxes.

It is the object of my invention to provide a box of molded material, such as a box that is produced from synthetic resins, which will be very strong, light in weight, and utilize the minimum of the expensive synthetic resin material out of which it is made.

It is a further object to have a box in which the internal structure of the base of the box is completely enclosed.

It is an object to have a box in which the base of the box is reinforced, so that the interior of the box and the exterior of the box bottom are reinforced by interconnecting ribs, will present a unitary structure that is light and strong, and will receive and position on the inside of the bottom of the box a support for watches, jewelry and the like.

Referring to the drawing:

20 Figure 1 is a top plan view of the box.

Figure 2 is a section on the line 2—2 of Figure 1, looking in the direction of the arrows.

Figure 3 is a section on the line 3—3 of Figure 1, looking in the direction of the arrows.

25 Figure 4 is a bottom plan view of the box with a part of the bottom cover broken away.

Figure 5 is a section on the line 5—5 of Figure 4.

Referring to the drawing in detail, the box 30 comprises a bottom 1 and a hinged cover 2. The hinged cover is held on the bottom by the spring metal clip 3.

The inside of the box at the bottom is formed with a rectangular depression comprising the 35 side walls 4 and bottom 5. In this depression is mounted an arcuate convex support 6 for an article to be displayed.

These side walls 4 are joined to the outer side walls 6a by a plurality of spaced ribs 7. Between the ribs 7 is the space 8, and between the wall 6a and the wall 4 there is a space open at the bottom. This open space is enclosed by a bottom panel 9, which is glued or otherwise at-

tached to the bottom 5 on its under side by the adhesive 10. This bottom 9 is cut away as at 11 to clear the ribs 7. The edges of the closure 9 engage and are located inside of the side flange 12, which surrounds the bottom of 5 the outside wall of the box bottom.

It will thus be seen that the walls of synthetic resin constituting the outer walls and the inner walls are very thin relative to the total dimensions of the box. They are structurally reinforced by the ribs extending from one wall to the other, and this unsightly rib structure and reinforcing is completely covered by a bottom panel 9, which presents a neat appearance. This panel may be a sheet of synthetic resin or a 15 sheet of cardboard.

It will be further understood that my box is comprised of a frame-like base, having a box-like depression and a bottom below it; and has a cover hinged to one end of the base and adapted to close down upon the upper surface of the base.

It will be understood that I desire to comprehend within my invention such modifications as may be necessary in order to adapt it to varying conditions and uses.

Having thus fully described my invention, what I claim as new and desire to secure by Letters Patent, is:

A display container for wrist watches or the like comprising a hollow base having a depending portion providing a recess in the upper side of the base, a hollow crown-shaped cover for the top of the base hingedly connected to an end thereof, a crown-shaped saddle adapted to rest 35 within the recess of the base, said saddle adapted to display a wrist watch, ribs connecting the depending portion and the side walls of the hollow base, a bottom cover plate secured in position over the depending portion and the ribs 40 for the purpose of providing a flush bottom for the base.

BENJ. S. KATZ.
